UNITED STATES PATENT OFFICE.

CEPHAS B. ROGERS, OF MERIDEN, CONNECTICUT, ASSIGNOR TO C. ROGERS
AND BROTHER, OF SAME PLACE.

DESIGN FOR CASKET-HANDLE SOCKET.

Specification forming part of Design No. 6,640, dated May 6, 1873; application filed April 3, 1873.

To all whom it may concern:

Be it known that I, CEPHAS B. ROGERS, of Meriden, in the county of New Haven and State of Connecticut, have invented a new Design for Casket-Handle Sockets; and I do hereby declare the following, when taken in connection with the accompanying drawing and the letters of reference marked thereon, to be a full, clear, and exact description of the same, and which said drawing constitutes part of this specification, and represents in—

Figure 1 a front view.

This invention relates to a design for the socket or plate by means of which the handle is attached to the casket; and it consists in the peculiar configuration of the socket, as more fully hereinafter described.

In outline the socket is of oblong form, the two sides parallel, the two ends of semicircular form. From the edge the plate rises toward the center to the socket proper or point where the lever is attached. The surface is preferably ornamented by a border and tracing each side of the lever-seat, but the ornamentation is no part of this design.

I claim as my invention—

A design for a casket-handle socket, as shown in the accompanying illustration, and herein described.

CEPHAS B. ROGERS.
